UNITED STATES PATENT OFFICE.

PAUL C. RAWLS, OF DES MOINES, IOWA, ASSIGNOR TO ERNEST HAUSBERG, OF CHARLES CITY, IOWA.

ELECTRICALLY-OPERATED TYPE-WRITER.

1,186,941.

Specification of Letters Patent. Patented June 13, 1916.

Application filed February 3, 1911. Serial No. 606,324.

To all whom it may concern:

Be it known that I, PAUL C. RAWLS, a citizen of the United States, residing at Des Moines, in the county of Polk and State of Iowa, have invented a certain new and useful Electrically-Operated Type-Writer, of which the following is a specification.

My invention relates to that class of typewriters in which the operator need apply only a slight pressure to the keys and the corresponding type bars will then be automatically actuated by electricity.

More specifically it refers to certain improvements in electrically operated typewriters such as illustrated and described in the application of Ernest Hausberg, for United States Letters Patent, filed October 13, 1909, Serial Number 522,413, Patent 1,156,288, Oct. 12, 1915.

20 The object of my present invention is to provide means of a simple, durable and inexpensive construction, whereby the establishment, by a contact at a key, of a circuit through any one of the selective magnets will automatically, and without any action 25 or effort of the selective magnet itself or its armature, establish a second and independent circuit through the universal operating magnet.

30 A further object is to provide improved means of simple, durable and inexpensive construction whereby the establishment of a circuit by an electric contact at a key will cause the operating magnet to operate a type bar through a full stroke even though the contact at the key be broken before the stroke is completed.

35 A further object is to provide means of simple, durable and inexpensive construction for causing a type bar to be moved to printing position upon the establishment of a contact at a key and to be returned to normal position even though the operator fails to remove his finger from the key and the contact remains unbroken.

40 A further object is to provide an arrangement of selective magnets and type bar operating devices that will be simple, durable, compact and not likely to get out of order.

50 My invention consists in certain details, in the construction, arrangement and combination of the various parts of the device, whereby the objects contemplated are attained, as hereinafter more fully set forth,

pointed out in my claims and illustrated in the accompanying drawings, in which:

Figure 1 shows a vertical, central, sectional view of a typewriter embodying my invention, and Fig. 2 shows a top or plan view of same with the carriage removed and parts of the cover broken away to show the interior construction.

Referring to the accompanying drawings, I have used the reference numeral 10 to indicate generally the typewriter frame and 11 the carriage having a platen 12 thereon. The frame and carriage are of the ordinary construction. At the front of the frame is a series of keys 13 arranged to slide vertically, the lower end of each key being supported upon a circuit closing spring 14. These springs 14 are supported at their inner ends on the cross bars 15 from which they are insulated by the strips 16. Introduced at the rear of the frame are the electrical conducting wires 17 and 18 designed to be connected to a suitable source of electrical supply not shown. The wire 18 is connected to a conductor plate 19 insulated from the frame by the insulator strip 20. Below each row of keys is a conductor cross piece 21 in electrical connection with the conductor plate 19 and in position to be engaged by the forward end of the adjacent conductor spring 14 when the corresponding key is depressed. Connected with each of the conductor springs 14 is a conductor wire 22 connected with an electromagnet 23. From each of the electromagnets 23 there is a conductor wire 24 leading to a universal conductor rod 25 which is connected to the wire 17 so that upon the depression of any key bar a circuit is established through one of the electromagnets 23. It is essential that there be one electromagnet 23 for each key and in order to assemble the comparatively large number of said electromagnets required in a machine of this kind I have arranged them in two rows, the lower row being supported on a cross bar 26 and the upper row being supported on a cross bar 27 which is above and in the rear of the cross bar 26, and the magnets 23 of the upper row are arranged in staggered positions relative to those on the lower row, as clearly shown in Fig. 2. These magnets 23 will be herein-after referred to as selective magnets and

there is provided for each of said selective

magnets a corresponding type bar and a series of levers for operating it. At a point between the two rows of selective electro magnets is a supporting cross bar 28 and for each selective magnet there is an armature 29 pivoted to the cross bar 28 and having a lever 30 fixed to it and extended rearwardly and provided at its rear end with a slot 31. The armatures for the upper row of selective magnets extend downwardly and those for the lower row extend upwardly in line with each other so that all of the levers 30 are in line. The alternate ones of the armatures 29 are extended downwardly but on the downwardly extended ones the corresponding magnets are in front so that on the establishment of a circuit through one of the lower magnets the armature is pulled forwardly and the lever 30 is moved downwardly at its rear end, while on the upper row of magnets the armature 29 moves rearwardly toward the magnet and the corresponding lever is moved downwardly at its rear end. This arrangement of parts makes a very compact and inexpensive construction well adapted for the work for which it is intended.

The type bars are indicated by the numeral 32 and are of the ordinary construction designed to coöperate with the platen in the ordinary way. For each type bar there is a link 33 and a lever 34 connected with said link. These levers 34 are pivoted to a cross bar 35 and there is a link 36 for each of said levers between its upper and lower end. Each link 36 is connected to a lever 37 hereinafter referred to as the type bar operating lever. Each of the levers 37 is provided with a hook 38 extended rearwardly and with a pin 39 to enter the slot 31 of the corresponding lever 30. The lower end of each of the type bar operating levers 37 is pivoted to an arm 40 and these arms are all pivoted to a cross bar 41 and said arms extend rearwardly from their pivotal point. A spring 42 is provided for each of the arms 40 to yieldingly hold it and the type bar operating lever 37 to its upward limit of movement. The operation of this part of the device is as follows: Assuming the parts to be in the positions shown in Fig. 1, and assuming that any one of the keys is depressed, then a circuit is established through the corresponding selective magnet. The corresponding lever 30 is depressed which carries with it the corresponding type bar operating lever, thus moving the hook 38 downwardly. This movement of course does not in any way affect the type bar which is moved by a universal operating bar hereinafter described, and immediately upon the breaking of the circuit the spring 42 will elevate the type bar operating lever 37.

65 The means for producing a striking

movement of the particular type bar corresponding to the key that has been depressed comprises an electromagnet 43 hereinafter referred to as the operating magnet, or universal operating magnet and which is connected by a wire 44 with the wire 17 and a wire 45 leads from the operating magnet 43 to the wire 18, there being included in said wire 45 a circuit making and breaking device hereinafter described. 70 The armature for the operating magnet is indicated by the numeral 46 and is carried by a bell crank lever 47 fulcrumed at 48. One end of the bell crank lever extends forwardly and is designed to engage a cross piece 49 to limit the forward movement of the armature 46 in a direction away from the magnet. Carried by the armature 46 is a bell crank lever 50 having its forwardly extended arm provided with a hook 51 and also having a downwardly projecting arm. This bell crank lever is designed to coact with a second bell crank lever 52, which lever is fulcrumed at 53 to a universal type bar operating bar 54 and said bell crank lever 52 is provided at its rearwardly extending end with a hook 55 and it is also provided with a downwardly projecting arm. The said hooks 51 and 55 are designed to coact with each other in 95 such a manner that when they are in engagement as shown in Fig. 1 and the armature 46 is moved rearwardly the bar 54 will also be moved rearwardly and when the hooks 51 and 55 have been separated 100 and the armature 46 moves forwardly the said hooks will reengage with each other.

In order to provide for automatically releasing the hooks 51 and 55, I have provided a plate 56 slidingly and adjustably 105 supported on the block 57 by means of a set screw 58. This plate is provided with a slot 59 through which the downwardly extended arm of the lever 50 is projected and the forward edge of said plate 56 110 stands in position close to the downwardly projecting arm of the lever 52 so that as said levers 50 and 52 are jointly moved rearwardly toward the operating magnet they will both move a short distance and 115 then the downwardly projecting arm of each will strike upon a part of the plate 56. This will cause the hook 51 to move upwardly and the hook 55 to move downwardly. In order to provide for adjusting the plate 56 so that this releasing movement of said hooks will take place in proper time relative to the operation of the type bars, I have provided a screw threaded rod 60 in the machine frame seated in a 120 block 61 on the plate 56 so that the operator may, by manipulating this rod 60, adjust the plate 56 forwardly or rearwardly so that the disengaging movement of the hooks 51 and 55 may be made to take place 125 130

at the desired time relative to the operations of the other parts of the machine.

If the operator desires, he may manipulate the rod 60 in such a way—that is, 5 adjust it so far rearwardly—that the projecting arms will not strike upon it at all, so that the hooks will not be released; a contact at the key then serving simply to cause the type bar to strike against the 10 platen but not to return to normal position without a release of the key.

The universal type bar operating bar 54 extends transversely across the machine and is supported at its ends by the arms 61 pivoted to the sides of the machine frame 15 so that said bar 54 may swing forwardly and rearwardly. The upper edge of said bar is preferably beveled at 62 in an upward and rearward direction. A contractile coil 20 spring 63^a is provided for normally holding the bar 54 to its forward limit. There is also a contractile coil spring 64 for holding the bell crank lever 47 and the armature 46 to its forward limit. The operation of this 25 part of the device is as follows: Assuming that one of the type bar operating levers 37 has been moved downwardly, as previously set forth, its hook 38 will then be in the rear of the bar 54, then upon the establishment of 30 a circuit through the operating magnet the armature 46 will be thrown rearwardly and this will cause the engaging hooks 51 and 55 to move the bar 54 rearwardly. This rearward movement of the bar 54 will move the 35 upper end of the lever 37 rearwardly which will operate the corresponding type bar. During the rearward movement of the lever 37 the pin 39 will slide rearwardly in the slot 31 of the lever 30, so that after the hook 40 38 has been moved into position for engaging the bar 54, the operation of the type bar is effected without moving the selective magnet or its armature or affecting the relation between them. As soon as the type bar 45 movement has progressed to the desired amount for practical use the downwardly extending arms of the levers 50 and 52 will strike upon their corresponding portions of the plates 56 so that said hooks will be released and as soon as they are released the 50 spring 63^a will move the bar 54 forwardly to its normal position, and as soon as the armature 46 is released from its magnet the spring 64 will move it to its forward limit 55 and when in this position the hooks 51 and 55 will reengage with each other ready for another operation.

The means for establishing a circuit through the operating magnet and for 60 maintaining it until the completion of the operating stroke of a type bar, regardless of the time when the initial circuit through the selective magnet is broken, comprises the following mechanism; the numeral 65 65 indicates an electromagnet con-

nected at both ends with the wire 18. This magnet, which is seen to be in circuit with each of the selective magnets, may be referred to as a circuit closing, or relay, magnet. Pivotedly supported adjacent to 70 the electromagnet is a lever 64 carrying an armature 65 at one end to coöperate with the magnet and having thereon a circuit closing arm 66 and also a locking arm 67. A spring 68 is connected with the lever 64 to 75 normally hold it in its position with the armature spaced apart from the magnet.

Fixed to a suitable part of the machine frame is a stationary contact arm 69 so arranged that when the armature is drawn to 80 the magnet the contact arms 66 and 69 will be in engagement. The said arm 69 is connected electrically with the wire 18 by the wire 70.

Mounted on the machine frame is a locking lever 71 having a shoulder 72 and an arm 73 arranged to project downwardly in the path of the armature 46. A spring 74 is provided for normally holding the arm 73 in a direction away from the operating magnet 43. The practical operation of this part of the device is as follows: When the parts are in the positions shown in Fig. 1 and a circuit is established through the wire 18 by the depression of any key, then the electromagnet 63 is energized and the armature 65 is drawn toward it. This will cause the circuit closing arms 66 and 69 to engage with each other and close a circuit through the electromagnets 43 and it will also bring the 90 locking arm 67 into position in engagement with the shoulder 72 of the lever 71. These parts will obviously be held in this position by means of the locking arm and coacting shoulder until such time as the armature 46 moves toward its magnet 43, whereupon the upper end of the arm 71 will be moved forwardly and downwardly to thereby release the locking arm 67 from the shoulder 72, whereupon, when the circuit is broken, the 100 armature 65 may move away from its magnet and assume the position shown in Fig. 1, thus breaking the circuit through the circuit closing arms 66 and 69. Obviously however this circuit cannot be broken through the 110 operating magnet 43 until after the armature 46 moves toward the magnet 43 and a type bar stroke has been completed.

In order to prevent sparking between the contact springs 14 and the cross rods 21, 120 I have provided a condenser 75 electrically connected with the wires 17 and 18 and properly insulated from the frame of the machine by the insulating material 76. The operation of this condenser is as follows: 125 When a circuit has been established through any of the selective magnets then the current is free to flow into the condenser and as soon as the circuit is broken at any key the current will be absorbed by the con- 130

denser to such an extent as to prevent sparking between the contact points of the springs 14 and the cross rods 21, thus avoiding the burning out of the electric contact points 5 at these places.

In practical operation with my complete typewriter any type bar may be operated by such pressure upon the corresponding key as is necessary to move the key supporting contact spring 14 downwardly into engagement with its corresponding rod 21 and it does not matter how light or how heavy the pressure on the key may be so long as this single result is accomplished.

In practice I preferably use relatively light springs 14 so that a very slight pressure upon any key is all that is necessary to complete the circuit. By this arrangement, I have found that the speed of operation by an ordinary operator may be increased to a very considerable extent on account of the fact that it is necessary only to touch a finger to a type key and the operator need not exert the force upon each key necessary to operate the entire type bar mechanism and he need not exercise any care whatever as to the uniformity of the pressure upon the various keys. Immediately upon the establishment of a circuit through a spring 14 and the corresponding cross piece 21 a circuit is established in the corresponding selective magnet. This immediately moves the type bar operating lever downwardly so that its hook 38 is in the rear of the upper edge of the universal type bar operating bar 54. At the same time as the circuit is established through one of the selective magnets 23 a circuit is also established through the electromagnet 63 and its armature is drawn to the magnet and a circuit established through the operating magnet, thus causing the coacting hooks 51 and 55 to move the universal bar 54 rearwardly in the machine and operate the corresponding type bar.

One of the advantages of my improvement is that, although the contact for closing the circuit of the power magnet is made when the selective armature is drawn toward its magnet, yet the movement of the selective armature itself does not make the contact, the selective magnet being relieved of every function except that of moving the type bar operating mechanism into position for being operated.

Another of the advantages of my improvement is that the key need only be depressed for the shortest possible space of time and thereafter the mechanism that operates the corresponding key bar will complete its operation regardless of the period of time when the operator releases the key for the reason that a circuit is established through the operating magnet

and this circuit is maintained until it is 65 cut off by the mechanical operation of the armature 46 moving toward its magnet and operating the type bar.

In a machine of this class it is obvious that the impact of all of the type bars upon the platen will be substantially uniform for the reason that each type bar is operated by the same operating mechanism.

The automatic circuit closing device comprising the electromagnet 63, the lever 64 70 and the locking lever 71 performs a very advantageous result in machines of this kind in that it insures the positive operation of the operating magnet and a full stroke of each type bar regardless of the 80 amount of time that any of the keys has been depressed.

Another advantageous feature of my invention is the arrangement of the mechanism for connecting the type bar operating levers 85 37 with the universal bar 54. In this connection the arrangement is such as to avoid all possibility of any of the hooks 38 remaining in such position as to engage the universal bar 54 at any time other than the time 90 when the corresponding key is depressed. In this connection it is to be understood that the coacting hooks 51 and 55 are automatically released from each other during the time that the armature 46 moves to its magnet and the time of such release may be varied to suit the requirements by a manipulation of the screw threaded rod 60. Therefore as soon as the hooks are released the universal bar 54 returns to its normal position as shown in Fig. 1, thus immediately throwing it forwardly out of contact with the corresponding hook 38 which is then free to rise by the pressure of its spring 42 during the time that the type bar is returning to its normal position. With a rigid connection between the universal bar 54 and the armature 46 the said bar would be held at its rearward limit of movement until the armature 46 had completed its return movement and if the type keys were not depressed in very rapid succession it might be possible that one of the hooks 38 would fail to be disengaged from the universal bar 54 until after another one of the hooks 38 105 had been moved downwardly by its selective magnet. However by means of my improvement in this connection the hooks 51 and 55 are released from each other just prior to the time that the armature 46

110 strikes its operating magnet and the universal bar 54 is immediately returned by its spring to normal position which may be a considerable period of time prior to the time when the armature 46 returns to its 115 normal position.

Another advantageous feature of my invention is the employment of a condenser

in a machine of this class for the purpose of preventing sparking between the electric contact points.

I claim as my invention:

5. 1. In an electrically operated typewriter, the combination of keys, selective electromagnets, means for establishing an electric circuit through a corresponding selective magnet when a key is depressed, type bars, 65
10. a type bar operating device for each type bar, means actuated by a selective magnet for moving the type bar operating mechanism of a corresponding type bar to position for another operation upon the completion 70
15. of an electric circuit through the selective electromagnet, a universal operating electromagnet, an armature for it, means operated by said armature for operating a type bar operating device when the latter has been moved to position for being operated, an electromagnet connected in series with each of the selective magnets, and 75
20. means operated by said magnet for establishing a circuit through the operating magnet.
25. 4. In an electrically operated typewriter, the combination of a series of selective electromagnets, said magnets being arranged in two rows, one above the other, and one of the rows being in the rear of the other, and the magnets of the upper row being arranged in positions staggered with relation 80
30. to those of the lower row, a cross bar between the two rows of magnets, an arm for each magnet connected to said cross bar, an armature on each arm adjacent to the corresponding magnet, an arm for each of 85
35. said armatures, all of the latter arms being extended in the same direction, and said parts being so arranged that when an armature of the upper row is moved toward its magnet it will move its said arm downwardly and when an armature of the lower row is moved forwardly toward its magnet it will also move its said arm downwardly, 90
40. type bars, and a type bar operating device for each type bar, each of said type bar operating devices being operatively connected with one of said arms, for the purposes stated.
45. 5. In a typewriter of the class described, the combination of type bars, a type bar operating device for each type bar, a hook for each type bar operating device, a bar in position adjacent to said hooks, means for moving any one of said hooks to position for engaging said bar, an operating 100
50. magnet, an armature therefor, two connecting hooks, one being connected with said armature and the other with said bar and being designed to engage each other, and means automatically operated by the movement of the armature toward its magnet for 105
55. releasing said hooks.
60. 6. In a typewriter of the class described, the combination of type bars, a type bar operating device for each type bar, a hook for each type bar operating device, a bar in position adjacent to said hooks, means for moving any one of said hooks to position 110
65. for engaging said bar, an operating magnet, an armature therefor, two connecting hooks, one being connected with said armature and the other with said bar and being designed to engage each other, and means automatically operated by the movement of the armature toward its magnet for 115
70. releasing said hooks.
75. 3. In an electrically operated typewriter, the combination of keys, a selective elec- 120
80. 75. 80. 85. 90. 95. 100. 105. 110. 115. 120. 125.

for engaging said bar, an operating magnet, an armature therefor, two connecting hooks, one being connected with said armature and the other with said bar, and being designed to engage each other, means automatically operated by the movement of the armature toward its magnet for releasing said hooks, and means for adjusting said releasing means to cause it to operate at any desired point in the movement of the armature toward the magnet.

7. In a typewriter of the class described, the combination of type bars, a type bar operating device for each type bar including a hook, a universal bar in position to be engaged by any of said hooks, said universal bar being capable of movement in a direction for operating any type bar and having its hook in position for engaging said universal bar, a bell crank lever pivoted to the universal bar and having a hook on one end, an operating electromagnet, an armature therefor, a bell crank lever pivoted to said armature and having a hook at one end to coact with the hook on the first mentioned bell crank lever, a plate slidably supported and in position to be engaged by both of said bell crank levers when the armature and universal bar move toward the operating magnet.

8. In a typewriter of the class described, the combination of type bars, a type bar operating device for each type bar including a hook, a universal bar in position to be engaged by any of said hooks, said universal bar being capable of movement in a direction for operating any type bar whose hook is in position for engaging said universal bar, a bell crank lever pivoted to the universal bar and having a hook on one end, an operating electromagnet, an armature therefor, a bell crank lever pivoted to said armature and having a hook at one end to coact with the hook on the first mentioned bell crank lever, a plate slidably supported and in position to be engaged by both of said bell crank levers when the armature and universal bar move toward the electromagnet, and means for adjustably supporting said plate.

9. In an electrically operated typewriter, the combination of selective electromagnets, keys, means operated by a key for establishing a circuit through the corresponding selective magnet, an armature for each selective magnet, a rearwardly extended arm connected with each armature and designed to have its rear end move downwardly as the armature moves toward its magnet, type bars, a type bar operating device for each type bar including a lever capable of up and down movement and pivotally supported at its lower end, each of said levers being pivotally and slidably connected with one of said arms, a spring for normally

holding each of said levers at its upper limit, a hook on each of said levers, a universal bar in position adjacent to said hooks and capable of being moved rearwardly, means for moving said universal bar rearwardly, and a spring for moving the universal bar forwardly, said parts being so arranged that when the universal bar moves forwardly, the said lever carrying the hook will be moved upwardly by its spring to position out of engagement with the universal bar.

10. In an electrically operated typewriter, the combination of keys, type bars, a selective magnet for each key, means for establishing an electric circuit through a selective magnet upon the depression of the corresponding key, a type bar operating device for each type bar, means operated by the selective magnet for moving said type bar operating device to position for being operated upon the depression of a corresponding key, a universal operating magnet, an armature therefor, means actuated by said armature for operating the type bar operating device when the latter has been moved to operative position, and a circuit closing device for the universal magnet, said device consisting of a magnet in circuit with each of the selective magnets, an armature for said magnet, and means operated by said armature for establishing a circuit through the universal operating magnet upon the completion of a circuit through said circuit closing magnet.

11. In an electrically operated typewriter, the combination of keys, selective magnets, means for establishing a circuit through a corresponding selective magnet when a key is depressed, type bars, a type bar operating device for each type bar, means actuated by a selective magnet, upon the completion of a circuit through it, for moving a corresponding type bar operating device to operative position, a universal operating magnet, an armature therefor, means operated by said armature for actuating a type bar operating device when the latter has been moved to operative position, a relay magnet in circuit with each of the selective magnets, and a circuit making and breaking device actuated by the said relay magnet for closing a circuit through the universal operating magnet.

12. In an electrically operated typewriter, the combination of keys, selective magnets, means for establishing a circuit through a corresponding selective magnet when a key is depressed, type bars, a type bar operating device for each type bar, means actuated by a selective magnet, upon the completion of a circuit through it, for moving its associated type bar operating mechanism to operative position, a universal operating magnet, an armature therefor, means actuated

ated by said armature for operating a type bar operating device when the latter has been moved to operative position, a magnet in circuit with each of the selective magnets, an armature therefor, and means operatively connected with said armature, and actuated upon and by the completion of a circuit through any selective magnet, for establishing a circuit through the universal operating magnet.

13. In an electrically operated typewriter, the combination of keys, selective magnets, armatures therefor, type bars, a universal operating magnet, a universal bar operatively connected therewith, a type bar operating device for each type bar including a lever capable of up and down movement and pivotally supported at one end so as to be capable also of movement backward and forward, an arm operatively connected with a selective armature and in sliding engagement with said lever, and a hook for said lever designed to engage the universal bar when a corresponding selective magnet is energized.

14. In an electrically operated typewriter, the combination of keys, type bars, a circuit closer for each key, a series of selective magnets, a universal operating magnet, a magnet in circuit with each of said selective magnets, and means operated by said magnet for establishing a circuit through the universal operating magnet.

15. In an electrically operated typewriter, the combination of keys, type bars, a circuit closer for each key, a series of selective magnets, a universal operating magnet, a magnet in circuit with each of said selective magnets, an armature therefor, means operatively connected with said armature for making an electrical contact for establishing a circuit through the universal operating magnet, and a latch for maintaining said contact.

16. In an electrically operated typewriter of the class employing selective magnets for moving type bar devices to position to be operated and a universal operating magnet for moving the selected type bar device to printing position, the combination of a magnet in circuit with each of said selective magnets, an armature therefor, and means operatively connected with said armature for closing the circuit of the universal operating magnet.

17. In an electrically operated typewriter of the class employing selective magnets for moving type bar devices to position to be operated and a universal operating magnet for moving the selected type bar device to printing position, the combination of a magnet in circuit with each of said selective magnets, an armature therefor, means operatively connected with said armature for closing the circuit of the universal oper-

ing magnet, and a latching device for holding it in closed position.

18. In an electrically operated typewriter the combination of keys, a series of selective magnets connected with the keys, type bars, an operating magnet for operating a type bar when the operating magnet is energized, a relay magnet energized upon and by the completion of a circuit through any selective magnet, means operated by the said relay magnet for closing the circuit through the operating magnet, and means for keeping it closed while a type bar is being operated.

19. In an electrically operated typewriter, the combination of keys, selective magnets, a relay magnet, means for energizing a selective magnet and the relay magnet by a single electrical contact at a key, type bars, an operating magnet, means for the operation of the type bars by the operating magnet, and a switching device operated by the relay magnet for closing the circuit through the operating magnet and keeping it closed while a type bar is being operated.

20. In an electrically operated typewriter, the combination of keys, selective magnets, a relay magnet, means for energizing a selective magnet and the relay magnet by a single electrical contact at a key, type bars, an operating magnet, means for the operation of the type bars by the operating magnet, and a switching device operated by the relay magnet for closing the circuit through the operating magnet.

21. In an electrically operated typewriter of the class employing a series of selective magnets for moving type bar devices to position to be operated, pivoted armatures for the selective magnets and a universal operating magnet for moving the selected type bar device to printing position, the combination of levers each operatively connected at one end with a type bar device and at the other with the said pivoted armature of a corresponding selective magnet, the said armatures extending alternately upwardly and downwardly and the corresponding selective magnets being arranged in two rows so as to draw said armatures backward and forward respectively for the purpose of bringing the type bar devices into position to be operated.

22. In an electrically operated typewriter, the combination of type bars, a type bar operating device for each type bar, means for moving any one of the said type bar operating devices to position for engaging the said operating bar, an operating magnet, an armature therefor, means for operatively connecting the said operating bar to the said armature, and means automatically operated by the movement of the armature toward its magnet for disconnecting the said operating bar therefrom.

23. In an electrically operated typewriter, the combination of keys, selective magnets for the keys, an armature for each selective magnet, type bars, a universal operating bar, and means for effecting an operative connection between a type bar and the universal operating bar when a corresponding selective armature is moved, said means including a sliding element whereby the universal operating bar may move and the corresponding armature and its magnet may remain stationary.

24. In an electrically operated typewriter, the combination of a series of selective magnets, armatures for said magnets, type bars, a universal operating bar for said type bars, a series of type bar operating devices each comprising a lever having a hook rigidly connected to it, the said lever being capable of bodily longitudinal movement whereby its hook may be brought into operative relation with the universal operating bar, and the said lever also being capable of pivotal movement whereby a movement of the universal operating bar will effect a printing movement of the corresponding type bar, and means for connecting the armatures with the said levers for moving them longitudinally when an armature is attracted to its magnet, said connection between the armatures and the said levers including a sliding element, whereby the selective magnet and its armature may remain stationary during the pivotal movement of the said lever.
